RETORT BURNER OF THE POT TYPE

Marc Resek, Cleveland Heights, Ohio, assignor to
 Perfection Stove Company, Cleveland, Ohio, a
 corporation of Ohio

Application August 2, 1946, Serial No. 688,100

7 Claims. (Cl. 158—63)

1

This invention relates, generally, to liquid fuel burners, and more particularly to those of the pot type, and it consists in incorporating in a burner of this type a liquid fuel vaporizing unit or retort, with the principal objects in view of increasing the efficiency and improving the performance of the burner by causing it to more readily and thoroughly vaporize or gasify the fuel and consequently produce a cleaner fire.

Another object is to provide a construction that facilitates priming or starting of the burner, as well as cleaning of the vaporizing unit, and which construction is relatively simple, inexpensive, compact and durable, and is not likely to get out of order.

These objects and advantages, with others that will become apparent from the following description, are attained in the construction illustrated in the accompanying drawing wherein Fig. 1 is a central vertical section through my improved vaporizing burner and the fuel supply and control means therefor, the latter being shown more or less conventionally, and Fig. 2 is a horizontal section through the burner in offset planes, as indicated by the line 2—2 of Fig. 1.

Similar reference characters designate similar parts in the two views.

The burner pot, designated generally by the reference numeral 1, includes a cylindrical peripheral wall 2 that merges at its lower end, through an inwardly curved portion of liberal radius, into a slightly downwardly and inwardly inclined bottom wall 4. The latter wall has a central opening within which is welded or otherwise secured a so-called lighting tube 5 that rises a substantial distance within the burner pot. Said tube depends a short distance below the pot and its lower end is turned outwardly to provide a flange 6. Secured to the upper end of the peripheral wall 2 is the flanged edge portion of an annular top wall 8 that is characterized by a relatively large central opening 10 surrounded by a depending flange 11.

Encasing the lower end of the burner pot 1, and secured thereto, desirably by welding, is an annular trough-like shield 15, the purpose of which will presently appear; and the burner pot assembly thus far described is supported centrally within a cylindrical housing 16 by a suitable number of L-shaped brackets 17 which have their inner ends fastened to said shield 15 and their upturned outer ends secured to the housing 16. Rising from the housing is a cylindrical casing 20, shown as having its lower end embedded in a gasket 21 of suitable packing material 58

2

confined in an upwardly facing channel of the housing, and an annular wall 23 extends inwardly from the casing 20 over and in spaced relation to the top wall 8 of the burner pot. Said wall 23 has a central opening 24 surrounded by a flange 25 that depends a slight distance into the opening 10 of the top wall 8 in concentric relation to the flange 11. The annular wall 23 defines the bottom of a combustion chamber which is enclosed by the upper portion of the casing 20, shown as broken away in part.

The vaporizing unit or retort is designated generally by the reference numeral 30 and, in its present preferred form, is made up of vertical tubes 31 and 32, and a cross tube 33, the opposite ends of the latter being communicatively connected to the upper ends of the vertical tubes by cruciform or X-shaped fittings 34. The branches of said fittings that are in alignment with the vertical tubes 31 and 32 are closed by screw plugs 35, while the branches that align with the cross tube 33 are closed by similar plugs 36. By removal of these plugs, convenient access may be had to the interior of all tubes for cleaning purposes. The tubes 31 and 32 are projected downwardly through apertures in the walls 23 and 8 and terminate at their lower ends a short distance above the bottom wall 4 of the burner pot. The lower end of the tube 31 is closed, as clearly shown in Fig. 1, and adjacent its lower end said tube communicates, through a pipe 37 with liquid fuel supply and control means designated generally by the reference numeral 40.

For the purpose of this disclosure the liquid fuel supply and control means 40 is shown as consisting of a receptacle 41, the interior of which is divided by a partition 42 into a receiving compartment A and a delivery compartment B. From a suitable source (not shown) liquid fuel is conveyed by a pipe 43 to the compartment A under the control of a valve 44 that is adapted to be closed in opposition to a spring 45 by a float 46, when liquid has risen within the compartment A to the level indicated by the broken line a.

Supported astride the partition 42, by a carrier 48, is an inverted U-shaped wick 50. The wick, by means of its carrier 48, is adjustable between a low position wherein the lower ends of its branches are well below the liquid level represented by the line a and a position wherein said ends are above said level; and the means for accomplishing this adjustment of the wick is herein disclosed as a screw 51 that is guided within an aperture of a bracket 52 that is carried by an end wall of the receptacle 41 and

has its lower end swiveled in a similarly supported bracket 53. The wick carrier 48 has a lateral extension 54 within a threaded hole of which the screw 51 operates. From this it is clear that, by turning the screw 51 by means of its knurled head 55, the wick carrier may be raised and lowered to effect the previously described adjustment of the wick 50.

A walled structure 60, in conjunction with the adjacent side of the lighting tube 5, encloses a priming basin or sump 61 within which is disposed the lower end of the vertical tube 31 of the retort 30. Said tube is provided with an orifice 62 intermediate the plane of the supply pipe 37 and the possible maximum liquid level in the priming basin or sump, indicated by the broken line a^2 (which, obviously from the disclosure, must be the same as that in the compartment A). When the wick 50 is adjusted with the lower ends of its branches below the liquid level indicated by the broken lines a and a' , fuel will, through the capillary and siphonic action of the wick, be transferred from the receiving compartment A to the delivery compartment B. From this latter compartment the fuel will flow through the pipe 37 to the tube 31 and thence through the orifice 62 to the priming basin 61, attaining substantially the same level therein as presently exists in the compartment B. At the start of an operation, the liquid level throughout the system will be that indicated by the broken lines a , a' and a^2 . Sustained by a holder 65 in the priming basin 61 is a lighting wick 66 which becomes saturated to its upper end by fuel from the priming basin.

The operation of the burner is started by lighting the wick 66 and, in the present instance, this is accomplished by means of an electrical igniter 67 in the form of a coil of resistance wire that is supported by and between electrodes 68 and 69, carried by a member 70, from which one of said electrodes is insulated in the usual manner, the other electrode being grounded through said member to the burner structure. Current is supplied to the insulated electrode through a conductor 71. The member 70 constitutes a closure for the lower end of the lighting tube 5, and is removably held in place by means indicated at 72. This detail forms no part of my present invention although its construction may be ascertained by reference to my copending application Serial No. 674,012, filed June 3, 1946.

When the apparatus is made ready for starting by lowering the wick 50 in the manner above described, fuel will accumulate in the priming basin 61 to the level indicated by the broken line a^2 . Current is then supplied to the igniter 67 and upon the same becoming incandescent fuel is vaporized from the top of the lighting wick 66 and ignited. Immediately thereafter, by reason of the resultant heat, additional fuel is vaporized from the surface of the body of fuel in the priming basin and before all fuel in said basin is consumed the tube 31 is heated to a sufficiently high temperature to vaporize fuel within the lower end of said tube. The vapors will then pass through the retort 30 and finally be discharged therefrom into the bottom portion of the pot 1, the process being continuous so long as fuel is supplied to the retort through the pipe 37. During the passage of the vapors through the tubes comprising the retort 30 they will be raised in temperature by heat resulting initially from the burning of the fuel in the priming basin and thereafter from the continued

operation of the burner thereby to promote vaporization or gasification to a high degree. The vapors, rising in the pot, are supplied with primary air through openings 2*, and this mixture is ignited in the first instance by the flame from the priming basin and as the mixture reaches the top of the bowl, secondary air is supplied thereto through the passageway between the walls 8 and 23 and the annular slot between the flanges 11 and 25, it being understood that air is supplied to the housing 16 by natural draft or by artificial means, such as a motor-driven air impeller (not shown). Substantially complete combustion then proceeds within the combustion chamber above the wall 23. The purpose of the shield 15 is to protect the bottom portion of the bowl from cool air entering the housing 16 in order to prevent such chilling of the bowl as would impair vaporization.

Having thus described my invention, what I claim is:

1. A liquid fuel burner comprising a pot provided with means for admitting air thereto, a retort structure enclosing a passage and arranged 25 with a part of said passage in heat receiving relation to the top of the pot and so that said passage will discharge into the pot, the pot incorporating a priming basin, and means for supplying fuel to the retort to a given level therein, 30 the retort having, adjacent its fuel receiving part, an orifice below said level through which liquid fuel overflows into the priming basin.

2. A liquid fuel burner comprising a pot provided with means for admitting air thereto, a 35 priming basin enclosed by the pot and situated adjacent the bottom of the latter, a retort supported by the pot with the fuel receiving end of the retort disposed within the priming basin and with the discharge end of the retort opening into the pot in laterally spaced relation to said basin, a portion of the retort intermediate said ends being disposed in heat receiving relation to the top of the pot, the retort having an orifice adjacent its fuel receiving end through 45 which liquid fuel overflows from the retort into the priming basin, and means for delivering fuel to the fuel receiving end of the retort to a level therein above the bottom edge of said orifice.

3. The combination defined by claim 2, plus: 50 means for vaporizing and igniting liquid fuel in the priming basin.

4. A liquid fuel burner comprising a pot provided with means for admitting air thereto, a retort structure enclosing a passage including 55 two vertical branches and a substantially horizontal portion through which the upper ends of said branches communicate, the retort being arranged with said horizontal portion of the passage in heat receiving relation to the top of the 60 pot and with said branches extending down the sides of the pot, one branch opening at its lower end into the pot and the other branch being closed at its lower end against direct communication with the pot, means for supplying fuel to the last mentioned branch of the retort 65 to a given level therein, and a priming basin incorporated in the pot with its top above said level, the retort having an orifice below said level through which liquid fuel overflows from said 70 last mentioned branch into the basin.

5. A liquid fuel burner comprising a pot provided with means admitting air thereto adjacent its top and additional means for admitting air to the pot at a lower elevation, a tubular retort comprising two vertical branches and a sub-

stantially horizontal branch through which the upper ends of the vertical branches are connected together for intercommunication, the retort being arranged with said vertical branches depending into the pot and with the horizontal branch in heat receiving relation to the top of the pot, the first of the vertical branches being closed at its lower end against direct communication with the pot, and the second vertical branch opening at its lower end directly into the pot, means for supplying liquid fuel to the first branch to a given level therein, and a priming basin in the pot with its top above said level, said first branch having an orifice below said level through which liquid fuel overflows into said basin.

6. Liquid fuel burning apparatus comprising a burner pot provided with means for admitting air thereto, a tubular retort comprising two vertical branches and a substantially horizontal branch through which the upper ends of the vertical branches are connected together for intercommunication, the retort being arranged with said vertical branches depending into the pot to near the bottom thereof and with the horizontal branch in heat receiving relation to the top of the pot, one vertical branch being closed at its lower end against direct communication with the pot, an open top priming basin situated within the pot, the lower end of the last mentioned branch being disposed within the priming basin, the other vertical branch opening at its lower end directly into the pot, liquid fuel supply and control means adjacent the pot at one side thereof, a pipe leading therefrom to the vertical branch of the retort that has its lower end disposed in the priming basin and through which pipe liquid fuel flows by gravity from said means to the retort, an instrumentality for maintaining a substantially constant fuel level in said means, and a second instrumentality through which feeding of the fuel from said means to the retort is governed, the top of the priming basin being above the aforesaid fuel

level, and the vertical branch of the retort that depends into said basin having an orifice through which liquid fuel overflows into the priming basin.

5 7. In a liquid fuel burner, a retort comprising two vertical branches and a substantially horizontal branch through the latter of which the upper ends of the vertical branches communicate, the retort being arranged with the horizontal branch in heat receiving relation to the heat output of the burner, the first vertical branch being closed at its lower end and the second vertical branch having its lower end open for delivery of vapors to the burner, means for supplying liquid fuel to the first vertical branch to a given level therein, and an open top priming basin in juxtaposition to the lower end of said first vertical branch, the top of said basin being above said level, and said first vertical branch having an orifice below said level through which liquid fuel overflows into said basin.
